UNITED STATES PATENT OFFICE.

JAMES C. DAVIS, OF HINSDALE, ILLINOIS, ASSIGNOR TO AMERICAN STEEL
FOUNDRIES, OF CHICAGO, ILLINOIS, A CORPORATION OF NEW JERSEY.

CORE-DRYING MEANS.

Application filed October 10, 1919. Serial No. 329,776.

To all whom it may concern:

Be it known that I, JAMES C. DAVIS, a citizen of the United States, residing at Hinsdale, in the county of Du Page and 5 State of Illinois, have invented certain new and useful Improvements in Core-Drying Means, of which the following is a specification.

This invention relates to core drying means.

At the present time, as is well known in the art, cores are dried in relatively large stationary ovens. The cores may be placed on portable racks which may be moved into and out of the stationary ovens. While such a core drying arrangement has its merits, I 15 find that I can greatly facilitate and reduce the cost of drying cores by a simple and novel means.

One object of my invention is to minimize the cost of drying cores.

Another object is to provide a simple and novel self-contained portable oven by means of which core drying may be facilitated.

Another object is to provide a core drying arrangement adapted to meet the various requirements for successful commercial operation.

These and other objects are accomplished by means of the arrangement disclosed on the accompanying sheet of drawings, in which—

Figure 1 is a longitudinal sectional view taken through one of my self-contained portable core drying ovens;

Figure 2 is a detail sectional view showing the means for sealing the sides of the oven with respect to the partitions therein to prevent leakage of hot gases;

Figure 3 is a plan view, somewhat diagrammatic, of a battery of stalls in which there are located a plurality of my core drying ovens connected to a hot gas supply source;

Figure 4 is a similar plan view, somewhat diagrammatic, showing the arrangement whereby the gases are exhausted from the ovens; and

Figure 5 is a detail sectional view showing the operation of the hot gas valve.

The various novel features of my invention will be apparent from the following description and the drawings and will be particularly pointed out in the appended claims.

Referring first to Figure 1 of the draw-

ings, it will be noted that my self-contained core drying oven includes a walled enclosure, the oven preferably including permanently arranged ends 10, top wall 11, and a bottom wall 12. The side walls are preferably removable and hinged at the top so that cores may be placed in and withdrawn from the oven with comparative ease. As here shown, the portable oven is mounted upon a truck 13 having wheels 14 for co-operating with tracks 15. Partitions 16, 17 and 18 are placed within the oven and spaced preferably from the end walls in an alternate manner so that hot gases which are admitted through an opening 19 in the lower compartment 20 are forced to take a definite path, which in this particular instance is circuitous, the gas finally being exhausted through an opening 21 in the top of the oven.

It will be noted that the partitions 16 and 18 are arranged in intimate contact with one end wall 10, and the other partition 17 is arranged in intimate contact with the other end wall 10, and partitions 16 and 18 are spaced from one of the end walls while the other partition 17 is spaced from the other end wall, the path of movement of the gases being indicated by the arrows.

It will be understood that the cores to be dried are placed upon the floor 12 and upon the partitions 16, 17 and 18. As the hot gases sweep through the circuitous route, all parts of the cores are treated for drying the latter in the most effective manner. The walls of the oven preferably are provided with insulation 22 for retaining the heat.

It will be noted that as a result of the arrangement of the partitions, four vertically arranged compartments are formed, compartment 20 heretofore mentioned and compartments 23, 24 and 25. Compartment 20 is the largest compartment and compartment 25 the smallest, the sizes of these compartments ranging from the largest to the smallest as shown. In this connection it will be noted that the hot gases enter the large compartment 20 and as these gases gradually give up their heat to the cores which are being dried, the gases become reduced in volume, and to have the same velocity of the heating gases throughout all of the compartments, the compartments above the largest 20 are gradually decreased in size.

To prevent leakage of the gases at the removable side walls, the latter, which are in the form of removable doors 26 preferably hinged at their upper ends 27, are provided on the inner side adjacent the various partitions with channels 28, by means of which sand 29 is carried. The sand is piled upon the channels 28 while the doors 26 are held partly open. In closing the doors 26, the same are swung inwardly, whereupon the side edges of the partitions project into the sand 29, forming a perfect seal.

By referring to Figure 3 of the drawings, it will be noted that I have provided a plurality of stalls 30 formed preferably in a brick structure 31 for the reception of the portable ovens, said wall 31 being provided with a plurality of hot gas passageways 32 connected with a furnace or source 33 of hot gases or hot products of combustion. These passageways 32 communicate with the openings 19 in one end wall of the associated portable ovens, whereby the hot gases 25 may be supplied to the latter. The openings 19 in the ovens preferably extend substantially the full width of the oven and may be of any desired height.

These passageways 32 are controlled by valves 34 so that if one of the stalls 30 is not occupied by an oven, the valve associated with said stall may be closed to prevent the escape of hot gases while such hot gases are being supplied to ovens located in other stalls. If desired, these valves may be automatically controlled by the oven in backing into place; that is to say, when the oven is moved into a position such that its opening 19 registers with the hot gas passageway 32, the valve 34 may be opened automatically.

For illustrative purposes in Figure 5, I have shown associated with the opening 19 an arm 35, which projects back into the passageway 32 for engaging and opening the valve 34 when the oven is backed into a position in which its opening 19 registers with the passageway 32. It will be understood that when the oven is withdrawn and, accordingly, the arm 35 withdrawn, the valve 34 will flap back into closed position to prevent further passage of hot gas from the source of supply. Each of the openings 21 in the top of the ovens, when in operative position, communicates with a gas outlet hood 36 having connected thereto a pipe 37, in turn connected to a general exhaust pipe 38 from which relatively cool gases are exhausted by a fan 39 operated by a motor 40.

The pipes 37 are provided with valves 41, whereby suction may be cut off at one of the stalls when the same is not occupied by an oven.

The cost of such a core drying arrangement is relatively inexpensive, for instead

of having a large brick oven and using the ordinary core drying frame on a car in the oven, this portable car is a self-contained oven, the structure of the ovens and the stall arrangement by means of which the ovens are charged with a drying medium being relatively simple and inexpensive. Another advantage is that instead of circulating hot gases in a large oven and undertaking to force the gases into and between the cores stacked on core shelves, I have provided an arrangement whereby the hot gases are forced to circulate in a definitely defined path, whereby the gases pass into intimate contact with the cores for drying the latter most effectively.

It will be understood, of course, that instead of providing the portable ovens with trucks, they may be shifted from one place to another by cranes.

The ovens in being moved away from the stalls 30 pass onto a transfer table 42, by means of which the oven may be moved into operative position with any suitable track 43 for movement to any desired part of the plant. Also by means of this transfer table, the ovens may be loaded at any desirable spot preparatory to being transferred to the stalls 30.

It is my intention to cover all modifications of the invention falling within the spirit and scope of the following claims.

I claim:

1. A portable oven comprising a walled enclosure, partitions therein forming communicating compartments in which the volume of the compartments decreases so that a fluid drying medium passing through said oven will be accommodated in accordance to its reduction in volume as a result of the lowering of its temperature.

2. A portable oven comprising a walled enclosure, partitions mounted in said enclosure arranged with respect to the walls for causing a fluid drying medium passing through said oven to take a circuitous route, the sides of said oven being removable and having means for co-operating with the partitions to form a seal against the leakage of gases.

3. A portable oven comprising a walled enclosure, partitions mounted in said enclosure arranged with respect to the walls for causing a fluid drying medium passing through said oven to take a circuitous route, the sides of said oven being removable and having sand containing portions for co-operating with the partitions to form a seal against the leakage of gases.

4. In combination, a supply stall having a passageway, a portable oven movable into and out of said stall said oven being an enclosed chamber having an opening which may register with the stall passageway, and means for supplying hot gases to said passageway.

sageway for causing a heating medium to pass through the oven.

5. In combination, a supply stall having a passageway, a portable oven movable into and out of said stall and having an opening which may register with the stall passageway, means for supplying hot gases to said passageway for causing a heating medium to pass through the oven, and means for causing spent gases to be exhausted from said oven.

6. In combination, a supply stall having a passageway, a valve associated therewith, a portable oven movable into and out of said stall and having an opening for registering with said passageway, said valve being controlled whereby a supply of hot gases may

pass through said passageway into the oven when the oven is in the proper position for receiving hot gases.

7. In combination, a supply stall having a passageway, a valve associated therewith, a portable oven movable into and out of said stall and having an opening for registering with said passageway, said valve being controlled whereby a supply of hot gases may pass through said passageway into the oven when the oven is in the proper position for receiving hot gases, and valve controlling means for controlling the exhaust of spent gases from said oven.

Signed at Chicago, Illinois, this 6th day of October, 1919.

JAMES C. DAVIS.
